UNITED STATES PATENT OFFICE.

CHARLES V. MCINTIRE, OF BROOKLYN, NEW YORK, ASSIGNOR OF ONE-THIRD TO LOUIS WILPUTTE AND TWO-THIRDS TO ALICE A. WILPUTTE, BOTH OF NEW ROCHELLE, NEW YORK.

GAS-COLLECTING MEANS.

Application filed October 4, 1919. Serial No. 328,522.

To all whom it may concern:

Be it known that I, CHARLES V. MCINTIRE, a citizen of the United States, and resident of Brooklyn, in the county of Kings and 5 State of New York, have invented certain new and useful Improvements in Gas-Collecting Means, of which the following is a specification.

The general object of my invention is to 10 provide improved gas collecting means for retorts, and particularly for by-product coke ovens.

The various features of novelty which characterize my invention are pointed out 15 with particularity in the claims annexed to and forming a part of this specification. For a better understanding of the invention, however, and the advantages possessed by it, reference should be had to the accompanying drawings and descriptive matter in which I have illustrated and described a preferred embodiment of my invention.

Of the drawings:

Fig. 1 is a sectional elevation of a portion 25 of a coke oven battery;

Fig. 2 is a section on the line 2—2 of Fig. 1;

Fig. 3 is a partial section on the line 3—3 of Fig. 2 but with the valve removed; and

Fig. 4 is a partial section on the line 4—4 of Fig. 1.

In the drawings A represents one of the coking chambers or ovens proper of a by-product coke oven battery of standard present day type. Connected to the usual gas outlet A' in the roof of the retort is an ascension pipe B formed as usual of a cast iron section and comprising a vertical portion and a horizontal portion connected to the 40 collecting main C which is formed of metal plate and runs lengthwise of the battery and separately connected to all the ovens thereof in the usual manner. A cleanout opening normally closed by a door B' is provided in 45 the convex side of the elbow connecting the horizontal and vertical branches of the ascension pipe.

The section B² forming the outer end of the horizontal portion of the ascension pipe 50 is secured to the side of the collecting main so as to open to the latter through a lateral opening C' in the collecting main. Advantageously, as shown, the end of the section B² projects through the opening C' and 55 the section is formed with flanges B³ and B⁴

riveted to the side and top walls respectively of the collecting main.

At the extreme end of the section B² a seat is formed for a sliding valve member D which is inserted and withdrawn through a kerf or slot B⁵ (see Fig. 3) formed in the section B² projecting over the top of the collecting main. Grooves B⁶ formed in the opposite side walls of the section B² below the kerf B⁵ constitute a guideway for the valve D. Advantageously, the ribs B⁷ forming the front walls of the grooves B⁶ are cut away as indicated at B⁸ somewhat above the bottom portion B⁹ of the valve seat.

The valve D may be drawn out of the section B² to connect the ascension pipe to the collecting main by any suitable means. As shown, a portable jack E is provided for this purpose, the jack comprising a lifting element terminating in a hook E' adapted to enter an eye D' formed in the external end of the valve member. When the valve D is put in place it may be hammered to its seat and the external joints between the valve D and the walls of the kerf B⁵ may be luted with fire clay. When the valve member D is withdrawn, the kerf B⁵ may be closed by luting clay alone, but preferably a removable slot closing member F is then inserted in the kerf B⁵ as shown in Fig. 3, and the joints between it and the section B² sealed by luting clay.

Those skilled in the art will readily recognize that the construction illustrated and described possesses important practical advantages and overcomes difficulties heretofore experienced, and arising from the severe conditions to which such apparatus is subjected in use.

In particular the hardened pitch and carbon deposits baking on the valve seat when the ascension pipe is in free communication with the collecting main, as it is during the greater portion of the time, cannot prevent the valve from being inserted and properly seated. The form and character of the valve and valve seat insure that the valve will cut away enough of these deposits to permit the valve to seat when it is hammered home. The cutting away of the ribs B⁸ permits the ready escape into the collecting main of the deposits cut out of the grooves B⁶ by the valve as the latter is forced home. Furthermore, the projection of the bottom B⁹ of the valve seat beyond the

adjacent side wall of the collecting main coupled with the shape of the latter permits these cuttings to fall directly into the stream of flushing liquor normally filling the lower portion of the collecting main. The connection of the ascension pipe directly into the side of the collecting main and the character and arrangement of the cut-off valve permits the use of an ascension pipe having a horizontal portion of minimum length. The form and location of the cut-off valve also minimizes stresses arising from the opening and closing of the valve and tending to open joints in the ascension pipe or its connection 15 to the oven.

While in accordance with the provisions of the statutes I have illustrated and described the best embodiment of my invention now known to me, it will be apparent to those 20 skilled in the art that changes may be made in the form of apparatus disclosed without departing from the spirit of my invention as set forth in the appended claims, and that under certain conditions some features of 25 my invention may be used to advantage without a corresponding use of other features.

Having now described my invention what I claim as new, and desire to secure by Letters Patent, is:

1. In combination a collecting main formed with a lateral opening adjacent its top, an ascension pipe having a horizontal portion secured to said main in register with 30 said opening and formed with a guideway at its end adjacent the main for a vertically

movable cut-off valve and a valve in said guideway.

2. In combination a collecting main formed with a lateral opening adjacent its top, an ascension pipe having a horizontal portion secured to said main in register with 40 said opening and formed with a guideway at its end adjacent the main for a vertically movable cut-off valve and a valve in said 45 guideway, said guideway opening at its lower end into said collecting main.

3. In combination a collecting main formed with a lateral opening adjacent its top, an ascension pipe having a horizontal 50 portion projecting through said opening and formed with a vertical guideway within the collecting main and with a slot at its top, a valve insertable in and removable from said guideway through said slot.

4. In combination a collecting main formed with a lateral opening adjacent its top, an ascension pipe having a horizontal portion projecting through said opening and formed within the collecting main with 60 grooves in its opposite sides and with a slot in its top wall and a valve insertable and removable through said slot and having its edges received in said grooves when inserted, the front walls of said grooves terminating 65 above the bottom of said horizontal portion.

Signed at New York in the county of New York and State of New York this third day of October A. D. 1919.

CHARLES V. MCINTIRE
Witness:

WILLIAM A. SHIELDS.
